UNITED STATES PATENT OFFICE.

THOMAS SAWERS AND WILLIAM E. EVANS, JR., OF BROOKLYN, NEW YORK.

AMUSEMENT APPARATUS.

Application filed June 9, 1927. Serial No. 197,699.

The present invention is concerned with the provision of an amusement apparatus of the character in which a passenger carrying conveyance is power driven along a predetermined course, and the passenger compartments are caused to move eccentrically as the carriage travels.

Preferably the traveling carriage conveyance mounts a rocking carriage. One or more passenger compartments are mounted on the carriage and eccentrically moved by the rocking motion of the carriage. Preferably also, the passenger compartments are given one or more additional movements either gravitationally or otherwise, which movements are entirely independent of the movement of the rocking carriage itself.

An object of the invention is to provide an amusement device of this general character so arranged that the passenger compartments will be suddenly moved and jerked about in various directions in order to provide amusement, excitement and unexpected thrills to the riders.

In a preferred embodiment of the invention, a number of travelling conveyances are operatively connected to an endless cable, and continuously caused to travel in an orbital path. Preferably the conveyance rolls over a platform bearing the rocking carriage. Track means is provided for preventing lifting movement of the conveyance itself, and additional track means is provided for imparting movement to the rocking carriage.

This second track means is preferably undulating, and carriage operating means is maintained in continuous engagement with the undulating track to impart the desired motion to the carriage.

The device in its preferred embodiment provides comparatively safe, although exciting amusement for the riders, and causes the passenger compartments to be subjected to a wide variety of compound motions which are quite bewildering. The particular manner in which the passenger compartments are associated with the carriage and with a set of mounting stairs causes an optical illusion which makes the travel seem considerably more dangerous than it really is. In fact, the riders while the device is in motion will be somewhat confused as to whether the passenger compartments, the carriage, the mounting stairs, or any or all of them happen to be in motion.

One novel feature of the invention is the

provision of an amusement apparatus which combines both the mechanical and positive movement of the carriage with gravitation or inertia controlled movements of the passenger compartments.

Other and more general objects of the invention are to provide an amusement apparatus of comparatively simple construction, which will be rugged and durable in use, and which may be built and operated with comparative economy.

With the above noted and other objects in view, the invention consists in certain novel features of construction and combinations and arrangements of parts, as will be more fully hereinafter set forth and pointed out in the claims. The invention may be more fully understood from the following description in connection with the accompanying drawings, wherein—

Fig. 1 is a diagrammatic broken top plan view showing the general arrangement of the conveyances, the platform over which they travel and the cable drive.

Fig. 2 is an enlarged top plan view of one of the conveyances.

Fig. 3 is a vertical sectional view through one of the conveyances and its supporting platform showing the two tracks, this view being taken approximately on the staggered line 3—3 of Fig. 4.

Fig. 4 is a vertical sectional view on the line 4—4 of Fig. 3.

Fig. 5 is a sectional detail taken approximately on the line 5—5 of Fig. 6.

Fig. 6 is a fragmentary sectional detail on the line 6—6 of Fig. 3.

Fig. 7 is an enlarged sectional detail on the line 7—7 of Fig. 4.

Figs. 8 and 9 are diagrammatic views in front elevation showing the positions assumed by the passenger carriers when the rocking carriage is in its two extreme positions.

Referring first to Fig. 1 I have used the reference character 10 to designate a floor or platform preferably enclosed by a railing 11 and accessible by a ramp or stairway 12. Beneath the platform 10 there is mounted a driving motor 13 acting through suitable power transmitting mechanism 14 to rotate a drum or pulley 15. An endless cable or other suitable flexible device 16 connects the driven pulley 15 with an idler pulley 17, and as the cable moves, it causes the movement of a connected series of conveyances 18 pro-

vided with rollers or casters 19 rolling over the platform 10. These conveyances are preferably connected to each other by links 20, and are each operatively connected to the 5 concealed cable 16 by mechanism which will be later described.

Preferably the conveyance 18 is in the nature of a flat car, as best seen in Figs. 3 and 4. A sleeve 21 projecting downwardly from the 10 under surface of the car passes through a slot 22 in the platform 10. Clamped to the sleeve below the platform is a split collar 23 bearing a rigid arm 24 which is pivotally connected as at 25 to a clamping member 26 15 adjustable by screws 27 to grip the cable 16 above mentioned. Thus the car 18 is caused to move with the driven cable.

The movement of the car along the slot 22 is additionally guided by the use of rollers 28 rolling against track plates 29 secured to the under face of the platform 10 at either side of the slot 22, these rollers are borne on laterally projecting stud shafts 30 carried by hangers 31 depending from the car 18.

25 A shaft 32 is journaled in bearing brackets 33 fixed upon the car 18, this shaft providing pivotal mounting for a skeleton rocking carriage designated generally at 34. Carriage 34 includes a pair of spaced parallel vertically 30 disposed skeleton side plates 35 rigidly connected together by cross frame bars 36. Side frame members 35 are of general triangular shape pivotally mounted at their lower apical ends on the shaft 32. A platform 37 has 35 limited gravitational sliding movement on the flat top of the rocking skeleton frame, this platform carrying suitable chair members 38 in which the passengers are seated.

Means is provided for intermittently rocking 40 the carriage 35 about its pivot shaft 32 as the car 18 travels over the platform 10. This means has been illustrated as a lever 39 vertically reciprocable through the hollow sleeve 31, and pivotally connected at its 45 upper end to a link 40 pivotally joined to a transverse shaft 41 connecting the two side members 35 of the rocking frame. Shaft 41 is disposed off-center relatively to the shaft 32, and the lower end of the link 39 is operatively connected to an undulating track 42 in 50 such a manner that the link 39 is reciprocated as the car 18 travels along.

Preferably track 42 is of general I-shape in 55 cross section and the link 39 at its lower end carries a yoke 43 mounting inwardly presented rollers 44 confined between the side flanges of the track 42.

I have already described the manner in 60 which the car 18 is locked against vertical movement relatively to the platform 10. As this car travels thereon, and the rollers 44 follow the contour of the undulating track 42, link 39 will be positively reciprocated to 65 positively rock carriage 34 about its pivot shaft 32.

The passenger carrying devices 38 include seat portions 45, side portions 46 and back portions 47, which are preferably provided with safety hand rails 48 adapted to be grasped by the passengers. Pairs of plates 49 depending from the members 38 pass through openings 50 in the platform 37. Pairs of shafts 51, 52 extending transversely of the carriage 34, are mounted in the plates 49, and at their ends carry rollers 53 disposed in generally V-shaped tracks 54 fixed to and depending from the platforms 37. The two adjacent shafts 52 are preferably connected by an equalizing bar 55 which assures parallelism of the two passenger carrying devices 38 in all positions of the rocking carriage 34. The use of the connected rollers 53 in the V-shaped tracks 52, 54 assures the maintenance of the seats 45 on an even keel in all positions of adjustment of the carriage, since 85 as the carriage tilts, changing the angular disposition of the tracks 54, the rollers 53 will move by gravity in the tracks. Inasmuch as the two sets of rollers of each passenger carrier 38 are fixed relatively to each other, there 90 will be no tendency of the passenger carriers to tilt. The equalizing bar 55 assists in the maintenance of the two passenger carriers on an even keel, particularly when sudden shocks are imparted to the carriers which might 95 cause them to travel by momentum, as when the carriage 34 comes to a sudden stop, or the sliding platform 37 reaches the end of its movement.

The tilting or rocking movement of the 100 carriage 34 is positively checked in both directions by the use of cables 60 anchored to the car 18 and connected to arms 61 fixed to the shafts 51.

The means for guiding the sliding movement of the platform 37 along the flat top of the carriage 34 by momentum is best seen in Figs. 5 and 6 wherein it will be noted that longitudinally extending rails 63 are mounted in brackets 64 on the top of the carriage. Guided for sliding movement along these rails are depending brackets 65 carried by the platform 37. Preferably marginal flanges 37^a on the platform 37 normally conceal the rods 63 from view, and serve as dust covers 115 for the cushioning springs 66 which encircle the rods 63 between each pair of brackets 64 and 65.

As best seen in Fig. 6, sliding movement of the platform 37 across the top of the carriage 120 34 is checked by the cushioning springs 66, these springs being of the coiled expansion type backed against the brackets 64 and compressed by the brackets 65.

Carried upon the cars 18 are stairways 75 125 by which the passengers enter and leave the elevated passenger carriers 38. These stairways are guarded by handrails 76 and may be suitably ornamented as by the lamps 77.

The operation of the device is substan- 130

tially as follows. With the cable 16 in motion, the connected train of cars 18 travel in an orbital path, the cars being guided by the slot 22, and held against upward movement 5 by the rollers 28.

As the car 18 travels along, rod 39 is acted upon by the undulating track 42 to rock the carriage 34. The carriage will first be rocked to the position of Fig. 8, at which 10 point further rocking movement is checked by one of the cables 60, and the momentum of the sliding platform together with the passenger carriers 38 is such, that it slides laterally after the carriage has been stopped. 15 The sliding movement of the platform is checked by the spring 66 in the manner above described. Upon continued movement of the car 18, carriage 34 is rocked in the opposite direction as shown in Fig. 9, and when 20 brought to a sudden stop by one of the cables, platform 37 will slide in the opposite direction carrying with it the passenger carriers 38. These carriers are always maintained 25 on an even keel by gravity due to the unique arrangement of the V-shaped tracks 54 and the rollers 53.

The combined travel of the car 18, rocking of the carriage 34, shifting of the angle of the carriage relatively to the passenger carriers and bodily sliding movement of the platform 37, serves to bewilder, surprise and amuse the riders. The presence of the mounting stairways directly in front of the passenger carriers, produces somewhat of 35 an optical illusion, since if the riders observe the steps, it is rather difficult to tell just what part of the conveyors is actually in motion.

Obviously, various changes and alterations 40 might be made in the general form and arrangement of parts described without departing from the invention. Hence we do not wish to limit ourselves to the details set forth, but shall consider ourselves at liberty 45 to make such changes and alterations as fairly fall within the spirit and scope of the appended claims.

We claim:

1. In an amusement apparatus, a car, a carriage mounted for rocking movement on the car, a passenger carrier on the carriage, means for maintaining the passenger carrier on an even keel as the carriage rocks.
2. In an amusement apparatus, a car, a carriage mounted for rocking movement on the car, and a passenger carrier on the carriage mounted for sliding movement relatively thereto, and means for maintaining the passenger carrier on an even keel as the carriage rocks.
3. In an amusement device, a car, a movable carriage on the car, means for intermittently rockably moving the carriage, a passenger chair on the carriage, and means whereby the chair moves by inertia whenever movement of the carriage is checked,

said carriage being mounted to tilt, said chair being slidably relatively to the tilting carriage and retaining on an even keel as the carriage rocks.

4. In an amusement device, a car, a movable carriage on the car, means for intermittently moving the carriage, a passenger chair on the carriage, means whereby the chair moves by inertia whenever movement of the carriage is checked, said carriage being mounted to tilt, said chair being slidably relatively to the tilting carriage, and means for maintaining the chair on an even keel in all positions of the carriage.

5. In an amusement apparatus, a car, a carriage mounted for rocking movement on the car, a passenger carrier on the carriage, and carriage operating means operable only when the car is in motion, comprising an undulating track, a rocker mechanism locked to the track.

6. In an amusement apparatus in combination, a floor having a slot therein, a car including roller means to travel on the floor, and guide means extending downwardly through the slot, a carriage movably mounted on the car, an undulating track, means operatively connecting the carriage and track to impart movement to the carriage as the car rolls along the platform, and a passenger carrier on the carriage.

7. In an amusement apparatus in combination, a floor having a slot therein, a car including roller means to travel on the floor, and guide means extending downwardly through the slot, a carriage movably mounted on the car, an undulating track, means operatively connecting the carriage and track to impart movement to the carriage as the car rolls along the platform, and a passenger carrier on the carriage, said carriage being rockably mounted.

8. In an amusement apparatus in combination, a floor having a slot therein, a car including roller means to travel on the floor, and guide means extending downwardly through the slot, a carriage movably mounted on the car, an undulating track, means operatively connecting the carriage and track to impart movement to the carriage as the car rolls along the platform, and a passenger carrier on the carriage, said carriage being rockably mounted, said track being disposed under the floor and the connecting means extending through the slot.

9. In an amusement apparatus in combination, a floor having a slot therein, a car including roller means to travel on the floor, and guide means extending downwardly through the slot, a carriage movably mounted on the car, an undulating track, means operatively connecting the carriage and track to impart movement to the carriage as the car rolls along the platform, and a passenger carrier on the carriage, said carriage be-

ing rockably mounted, said guide means including a sleeve, and said connecting means including a rod slideable vertically in the sleeve.

5 10. In an amusement apparatus in combination, a floor having a slot therein, a car including roller means to travel on the floor, and guide means extending downwardly through the slot, a carriage movably mounted on the 10 car, an undulating track, means operatively connecting the carriage and track to impart movement to the carriage as the car rolls along the platform, and a passenger carrier on the carriage, said carriage being rockably 15 mounted, said guide means including a sleeve, and said connecting means including a rod slideable vertically in the sleeve, said track being of general I-shape in cross-section, a yoke at the lower end of the rod straddling the track, and rollers mounted on the 20 yoke interlocking with the track flanges.

11. In an amusement device, a car, traction wheels thereon, a carriage rockably mounted on the car, a platform having limited 25 slideable movement on the carriage, said platform adapted to slide by inertia as the carriage reaches the limit of its rocking movement in either direction, passenger chairs carried by the platform, and means 30 for maintaining the passenger chairs on an even keel in all positions of the carriage and platform.

12. In an amusement device, a car, traction wheels thereon, a carriage rockably mounted

on the car, a platform having limited slide- 40 ble movement on the carriage, said platform adapted to slide by inertia as the carriage reaches the limit of its rocking movement in either direction, passenger chairs carried by the platform, and means for maintaining 45 the passenger chairs on an even keel in all positions of the carriage and platform, the chairs including depending extensions passed through the platform, rollers carried by the extensions and general V-shaped tracks de- 50 pending from the platform in which the rollers rest, whereby the chairs gravitation- ally assume a vertical position in all posi- 55 tions of the platform.

13. A device of the class described in claim 50 12, wherein shafts connect the rollers of each chair and an equalizer bar connects the roller shafts of adjacent chairs.

14. In an amusement apparatus, a car, a carriage rockably mounted on the car, a pas- 55 senger carrier slideable on the carriage and flexible devices anchored to the platform lim- 60 iting the sliding movement of the passenger carrier.

15. In an amusement apparatus, a car, a 60 frame rockably mounted on the car, passenger chairs supported on the frame, and a mounting stairway on the car arranged ad- 65 jacent the frame and in proper position to provide access to the chairs in all positions of the latter.
